CURRENT WAVE INDICATING APPARATUS

William J. Liska, Berwyn, Ill.

Application June 4, 1934, Serial No. 728,972

16 Claims. (Cl. 179—175)

My invention relates more particularly to means associated with, and operated responsive to, electrical amplifying apparatus, involving a speaker, more especially of the dynamic type, for visually indicating the wave forms of the electrical currents or variations thereof by which the speaker is energized, and where the sound produced by the speaker is within the range of audible frequency for audibly indicating the sound waves produced by the speaker simultaneously, and in synchronism, with the visual indication thereof.

The apparatus thus provided is highly useful in many fields, as for example in the electrical, radio and research industries, in physical laboratories for scientific research and in medical work where it is desired observations be made of pulsating movements within the human body, such as for example the action of the heart.

The visual portraying of the current waves responsive to which the electrically operated speaker is operated, enables the observer to visualize the exact wave form of the current; music, the voice, lag in current due to induction, or lead due to capacity being carefully portrayed. It permits of the studying of electric circuits by adding capacity or inductance thereto, the change effected thereby being rendered visible, and in the radio field is particularly useful in checking coils, condensers, speakers, and other electrical elements affecting the operation of the speaker.

While the feature of rendering the wave forms visible is of advantage, this feature in combination with the feature of rendering such wave forms audible simultaneously, and in synchronism, with the visual portrayal thereof, is of larger importance and value as thereby the observer is furnished a means of sensing to a much greater degree of accuracy, the wave forms, and performance, of the current supplied to the speaker, rendering the apparatus much better suited to its use in the many fields in which such apparatus is suitable for use and especially in the particular fields and for the special uses above set forth.

Referring to the accompanying drawing:

Figure 1 is a plan view, somewhat in the nature of a diagram, of apparatus embodying my invention, one of the elements of the apparatus being shown in section and the apparatus being viewed at the line 1 on Fig. 2 and in the direction of the arrow.

Figure 2 is a view in elevation of certain of the elements shown in Fig. 1; and

Figure 3, an enlarged edge view of a stirrup-member forming a part of the structure.

In accordance with my invention I provide a reflector, shown as a mirror represented at 3, so associated with a part of a speaker which is moved responsive to the varying current supplied thereto, as to cause the reflector to vibrate or move into different positions, preferably angularly, responsive to the current waves; and utilize the reflector to reflect to a receiving object, as for example a screen, a fixed beam of light directed against the reflector.

The speaker illustrated and shown somewhat diagrammatically and of well known construction, is of the dynamic type comprising a pole piece 4 of magnetic material mounted in a casing 5 and surrounded by an energizing coil 6 constantly supplied with exciting current from any suitable source of direct current supply, as from a battery represented at 7, or a direct current service supply.

The speaker also comprises a flexible cone dia- 20 phragm 8 which is held stationary at its outer marginal edge 9 by the casing 5 and is slidably supported at a tubular extension 10 on its smaller inner end on the outer end of the pole piece 4. Secured at its periphery to the diaphragm 8 and 25 at its yielding central portion 11 to the outer end of the pole piece 4 as by a screw 12, is a flexible spider 13 provided for the usual purpose.

A so-called voice coil 14 surrounds, and is secured to, the sleeve 10 of the diaphragm 8 so 30 that these parts are movable as a unit, the diaphragm 8 being vibrated responsive to changes in polarity of the voice coil 14 due to the variations in the current impressed thereon.

In the particular arrangement illustrated the 35 invention is shown as being utilized for testing a radio in which case the voice coil 14 would be connected with the voice coil leads represented at 15 of the radio apparatus which in the functioning of such apparatus for radio purposes 40 would connect with the voice coil of the radio speaker, the voice coil leads 15 being shown as extending from a speaker input transformer 16 as commonly provided in radios.

In the particular construction shown, and by 45 preference, the reflector 3, shown as a mirror, is carried by a stirrup-shaped strip 17 of flexible material, as for example press board, presenting divergent legs 18 and 19, connected, respectively, with the stationary pole-piece 4 and the dia- 50 phragm 8, and an intermediate portion 20 to which the reflector 3 is secured, the connections between the legs 18 and 19 and the intermediate portion 20 being in the nature of hinges, as for example by partially cutting through the mate- 55

rial of the stirrup crosswise thereof and along parallel lines as represented at 21 and 22. Thus as the diaphragm 8 vibrates back and forth responsive to the current input to the voice coil 14, 5 the mirror 3, due to the flexing of the stirrup 17 by the torque of the diaphragm in vibrating, will vibrate in response to the vibrations of the diaphragm.

The apparatus shown also comprises a lamp 10 23 or any other light source, for projecting a pencil beam of light, indicated at 24, against the mirror 3; a revolving polygonal mirror 25, shown as of octagonal shape and so positioned as to be impinged by the beam of light reflected by the 15 mirror 3 as represented at 26; a surface represented at 21 against which the beam of light reflected by the mirror 25, impinges, this surface being by way of example a screen upon which the reflected ray of light is rendered visible; and 20 an element, such as a piece of ground glass or a projecting lens as shown at 28, interposed between the polygonal mirror 25 and the screen 27 for projecting the moving image of the beam on the screen 27.

25 As will be readily understood from the foregoing, the light from the source 23, striking the mirror 3 will be deflected into different positions in its reflection to the rotating mirror 25 which latter reflects through the lens 28 and to the 30 screen 27 the beam of light reflected to it by the mirror 3, causing the image exhibited on the screen to be of wave form and having the characteristics of the vibrations of the mirror 3 and consequently of the current waves impressed upon 35 the voice coil.

The mirror 25 may be driven in any suitable way at a constant speed and at a rate suitable to the particular conditions presented by the apparatus being tested. Preferably an adjustable 40 speed motor represented at 29 would be employed, the motor being shown as driving the mirror 25 by means of a pinion 30 connected with the armature shaft of the motor and meshing with a gear 31 rigid with the mirror 25.

45 As will be understood according to the particular illustrated embodiment of my invention, the performance of the speaker is not only audibly, but visually, portrayed simultaneously responsive to the vibrations of the diaphragm 8, permitting 50 of a definiteness of analysis of current waves rendered heretofore impossible because of failure to coordinate the visual and audible portrayal of the different waves.

While I have illustrated and described a particular apparatus embodying my invention, I do 55 not wish to be understood as intending to limit it thereto as the same may be variously modified and altered without departing from the spirit of the invention.

60 What I claim as new, and desire to secure by Letters Patent, is:

1. In combination, an electrically-operated speaker having a vibratory element, and a structure, comprising a reflector, stationarily supported 65 at one portion and at another portion operatively engaging said element and movable responsive to the vibrations of said element.

2. In combination, an electrically-operated speaker having a vibratory diaphragm, and a structure, comprising a reflector, stationarily supported 70 at one portion and at another portion operatively engaging said diaphragm and movable responsive to the vibrations of said diaphragm.

3. In combination, an electrically-operated 75 speaker having a stationary pole-piece and a

vibrating diaphragm, and a structure, comprising a reflector, stationarily supported at one portion on said pole-piece and at another portion operatively engaging said diaphragm and movable responsive to the vibrations of said diaphragm. 5

4. In combination, an electrically-operated speaker having a vibratory element, and a structure comprising a flexible stirrup and a reflector on said stirrup between the legs of the latter, one of the legs of the stirrup being stationarily supported and the other leg thereof operatively engaging said element whereby the reflector is moved responsive to the vibrations of said element.

5. In combination, an electrically-operated 15 speaker having a vibratory diaphragm, and a structure comprising a flexible stirrup and a reflector on said stirrup between the legs of the latter, one of the legs of the stirrup being stationarily supported and the other leg thereof 20 operatively engaging said diaphragm whereby the reflector is moved responsive to the vibrations of said diaphragm.

6. In combination, an electrically-operated 25 speaker having a vibratory element, and a structure comprising a stirrup of flexible material presenting legs and an intermediate portion, the material of the stirrup at the junctures of said legs with said intermediate portion being of less cross sectional area than the remainder of the stirrup, said reflector being carried by said intermediate portion, one of the legs of the stirrup being stationarily supported and the other leg thereof 30 operatively engaging said element whereby the reflector is moved responsive to the vibrations of the element.

7. In combination, an electrically-operated speaker having a vibratory element, and a structure comprising a stirrup of flexible fibrous material presenting legs and an intermediate portion, the material of the stirrup at the junctures of said legs with said intermediate portion being of less cross sectional area than the remainder of the stirrup, said reflector being carried by said intermediate portion, one of the legs of the stirrup 40 being stationarily supported and the other leg thereof operatively engaging said element whereby the reflector is moved responsive to the vibrations of the element.

8. In combination, an electrically-operated 50 speaker having a vibratory element, and a structure comprising a stirrup of flexible material presenting legs and an intermediate portion, the material of the stirrup at the junctures of said legs with said intermediate portion being partially cut through to reduce the cross sectional area of the stirrup at these points, said reflector being carried by said intermediate portion of said stirrup, one of the legs of the stirrup being 55 stationarily supported and the other leg thereof operatively engaging said element whereby the reflector is moved responsive to the vibrations of said element.

9. In combination, an electrically-operated speaker having a vibratory diaphragm restrained 65 against movement at its peripheral margin and a pole-piece adjacent the center of the diaphragm and relative to which the diaphragm is movable, and a structure, comprising a reflector, secured at one portion to said pole piece and at 70 another portion engaging the movable portion of said diaphragm whereby said reflector moves responsive to the vibrations of said diaphragm.

10. In combination, an electrically-operated speaker having a vibratory diaphragm restrained 75

- against movement at its peripheral margin and a pole-piece adjacent the center of the diaphragm and relative to which the diaphragm is movable, and a structure, comprising a reflector, secured at one portion to said pole-piece and at another portion engaging said diaphragm between its inner and outer margins whereby said reflector moves responsive to the vibrations of said diaphragm.
- 10 11. In combination, an electrically-operated speaker having a vibratory diaphragm restrained against movement at its peripheral margin and a pole-piece adjacent the center of the diaphragm and relative to which the diaphragm is movable, and a structure comprising a flexible stirrup and a reflector on said stirrup between the legs of the latter, one of the legs of the stirrup engaging said pole-piece and the other leg thereof engaging said diaphragm between its outer margin and said pole-piece, whereby said reflector is moved responsive to the vibrations of the diaphragm.
- 15 12. In combination, an electrically-operated speaker having a flexible diaphragm, means for actuating the speaker for the production of audible sound, means for producing a light beam and means actuated by said speaker for causing said light beam to produce, simultaneously, and in synchronism, with the production of the sound waves by the movements of said diaphragm, a delineation, in the form of a wave line and observable simultaneously with the production of the audible sound, of the waves of current supplied to said speaker comprising a reflector in the path of said light beam and movable responsive to the vibrations produced by the speaker.
- 20 13. In combination, an electrically-operated speaker having a flexible diaphragm, means for actuating the speaker for the production of audible sound, means for producing a light beam and means actuated by said speaker for causing said light beam to produce, simultaneously, and in synchronism, with the production of the sound waves by the movements of said diaphragm, a delineation, in the form of a wave line and observable simultaneously with the production of the audible sound, of the waves of current supplied to said speaker.
- 25 14. In combination, an electrically-operated speaker having a vibratory element, means for actuating the speaker, means for producing a light beam, and means actuated by said element for causing said light beam to produce simultaneously, and in synchronism, with the vibrations of said element, a delineation in the form of a wave line and observable simultaneously with the vibrations of said element, of the waves of the current supplied to the speaker.
- 30 15. In combination, an electrically-operated speaker having a vibratory diaphragm, means for actuating the speaker, means for producing a light beam, and means actuated by said diaphragm for causing said light beam to produce simultaneously, and in synchronism with the vibrations of said diaphragm, a delineation in the form of a wave line and observable simultaneously with the vibrations of said diaphragm, of the waves of current supplied to the speaker.
- 35 16. In combination, an electrically-operated speaker having a vibratory diaphragm, means for actuating the speaker, means for producing a light beam, and means actuated by said diaphragm for causing said light beam to produce simultaneously, and in synchronism with the vibrations of said diaphragm, a delineation in the form of a wave line and observable simultaneously with the vibrations of said diaphragm, of the waves of current supplied to the speaker.

WILLIAM J. LISKA

40

synchronism, with the production of the sound waves by the movements of said diaphragm, an indication visual simultaneously with the production of the sound waves of the waves of current supplied to said speaker.

5 14. In combination, an electrically-operated speaker having a flexible diaphragm, means for actuating the speaker for the production of audible sound, means for producing a light beam and means actuated by said speaker for causing said light beam to produce, simultaneously, and in synchronism, with the production of the sound waves by the movements of said diaphragm, a delineation, in the form of a wave line and observable simultaneously with the production of the audible sound, of the waves of current supplied to said speaker comprising a reflector in the path of said light beam and movable responsive to the vibrations produced by the speaker.

10 15. In combination, an electrically-operated speaker having a vibratory element, means for actuating the speaker, means for producing a light beam, and means actuated by said element for causing said light beam to produce simultaneously, and in synchronism, with the vibrations of said element, a delineation in the form of a wave line and observable simultaneously with the vibrations of said element, of the waves of the current supplied to the speaker.

15 16. In combination, an electrically-operated speaker having a vibratory diaphragm, means for actuating the speaker, means for producing a light beam, and means actuated by said diaphragm for causing said light beam to produce simultaneously, and in synchronism with the vibrations of said diaphragm, a delineation in the form of a wave line and observable simultaneously with the vibrations of said diaphragm, of the waves of current supplied to the speaker.
